GEOCHEMICAL PROSPECTING SYSTEM

Herbert E. Metcalf, San Francisco, Calif., assignor, by mesne assignments, to Consolidated Engineering Corporation, Pasadena, Calif., a corporation of California

Application June 17, 1940, Serial No. 341,003

3 Claims. (Cl. 23—257)

My invention relates to a means and method for geochemical prospecting, and more particularly to a means and method of obtaining fluid samples of undisturbed soil below the surface of the earth, together with analysis of the samples and correlation of the results to obtain data indicative of the presence or absence of deeper mineral deposits. My invention has its widest application in prospecting surface layers of the earth for gases which have migrated from deeper petroliferous deposits.

Among the objects of my invention are: to obtain fluid samples from below the surface of the earth without any substantial atmospheric contamination thereof; to provide a means and method of obtaining substantially uncontaminated fluid samples from soil in situ; to provide a substantially uncontaminated soil fluid sample; to provide a gas and water sampling method which collects these fluids at a substantial depth beneath the earth's surface from substantially undisturbed soil; to provide an apparatus for obtaining fluid samples from soil in situ beneath the surface of the earth; to provide a means and method of trapping fluids from relatively undisturbed soil in a sample container; and to provide a simple and efficient means and method of obtaining fluid samples from soil beneath the surface of the earth.

My invention possesses numerous other objects and features of advantage, some of which, together with the foregoing, will be set forth in the following description of specific apparatus embodying and utilizing my novel method. It is therefore to be understood that my method is applicable to other apparatus, and that I do not limit myself, in any way, to the apparatus of the present application, as I may adopt various other apparatus embodiments, utilizing the method, within the scope of the appended claims.

In the copending application of Metcalf and Lawlor, Serial No. 341,004, filed June 17, 1940, entitled: Geochemical prospecting system, there was described and claimed a method and apparatus for aspirating liquid from soil in situ beneath the surface of the earth, and for directing this liquid into a sample container which is then sealed before being brought to the surface. In that application a means of supplying negative pressure to the container was used in order that available liquids in the soil be aspirated therefrom and pass into the container. The preferred means outlined for that purpose was an exhaust pump situated on the surface of the ground and connected with the container through the rod

by which the container was inserted into the ground.

In utilizing the system as outlined just above, any gas which existed in the soil, as gas, would be exhausted to the surface by the pump and would therefore not be present within the sample container. There are, of course, many types of prospecting where this loss of gas would in no way be significant, providing the analysis be confined wholly to the gas which is entrained, dissolved or otherwise held by the aspirated liquid. It has been found, however, that in other cases it is highly desirable to entrap and seal as a sample both the soil gas and the liquid without any substantial loss of either. Analysis is then made of the combined gas and liquid sample.

Broadly, therefore, my present invention involves as to method, preexhaustion of a container, which is sealed to maintain the negative pressure therein, and which is then inserted in the ground to a predetermined depth, punctured to cause gas and liquid from the soil immediately surrounding the container to enter thereinto, and then resealed in place to isolate from the atmosphere the fluids which have entered the container.

Preferably, as to apparatus, I prefer a rod to be driven or otherwise progressed into the ground, the end thereof carrying the exhausted container. Means are then provided to puncture the container so that the fluids may be drawn from the soil surrounding the container and rod into the container. Means are provided to reseal the container before withdrawal of the rod. I prefer to exclude atmospheric air from the container during the time that it is open so that practically its entire content is a fluid sample from soil relatively undisturbed beneath the surface of the earth. As stated above, the sample might comprise gas alone, gas and water or other liquid, or be almost wholly water in accordance with the water concentration at the location of taking the sample, which is preferably below the water table although not necessarily so.

In this regard, while I prefer to take my samples at uniform depths below the water table wherever possible, in case such uniform depth sampling is not feasible, correction is made for sampling depth below the top of the water table. Data for such corrections may be obtained by measuring the vertical significant sample constituent concentrations at a number of points in the area under investigation to establish a ref-

erence gradient. In any event, the sample obtained contains all the fluids that it is possible to force into the container by the difference of pressure between that in the original container and the surrounding soil. I prefer to leave the container open for a sufficient time so that these pressures may become equalized.

In the drawings:

Fig. 1 is a longitudinal, sectional view of a sampling rod having an exhausted container positioned therein, together with means for puncturing and resealing the container.

Fig. 2 is a diagram showing the puncturing position of cover and container; and

Fig. 3 is a diagrammatic view showing the resealing of the container after aspiration has occurred.

Fig. 4 is a plan view of the inner surface of the container cover showing the puncturing blade mounted thereon.

Fig. 5 is a diagrammatical view showing how the sampling rod is inserted into the earth.

Fig. 6 is a diagrammatic view of the manner in which the container is attached to a gas analysis apparatus.

Referring to the drawings for a more detailed description of my invention, a sampling rod body 1 is provided at its end with a pointed nose 2; this may be sharpened for driving into the ground or may be provided with cutting edges such as is customary on any drill bit for progression into the ground by rotation. Pointed nose 2 unscrews at joint 4 from the main body of rod 1 to open a container cavity 5 formed partly in nose 2 and partly in the main body of rod 1. In this cavity is mounted a sample container 6, this sample container is provided with a bottom 7 carrying thereon a fitting 8 provided with a threaded end 10 and diaphragm 11, this fitting being used for attachment of the container to a gas analysis system, as shown in Fig. 6. Bottom 7 also carries an exhaust tube 12, one end being peripherally sealed to the bottom 7 and the other end having been connected to a vacuum pump for exhaust of the container, this exhaust tube being melted later to form a terminal vacuum seal as in electric lamp exhaust practice. Container 6 is also provided with a top 14, this top being of standard tin plate material. The top also has a circular friction channel 15 therein, which is shaped to receive a circular friction ridge 16 on a can cover 17 when registered therewith and forced thereinto. Top and bottom 17 and 15, respectively, are attached to the side walls of container 6 with the usual roll seams 19, which are for prevention of leaks, preferably thereafter soldered.

Thus, container 6 with its side walls and top and bottom 7 and 15, respectively, is a vacuum tight receptacle which may be exhausted through exhaust tube 12 and thereafter sealed to preserve the vacuum therein.

Top roll seam 19 fits snugly against an inner shoulder 20 formed in the interior of cavity 5 and, if desired, a gasket may be used between roll seam 19 and shoulder 20 to prevent exhaustion of air from cavity 5. The pressure of seam 19 against shoulder 20 is provided by screwing nose 2 on main body 1, the container being fitted so that pressure of the threads 4 will force the two together. Before the container is locked in place, however, can cover 17 is positioned on a backing plate 21, which is concentric with the container, and this backing plate is supported by a flexible diaphragm 22 attached to the side walls of rod 1. Cover 17 is normally spaced from top 14 by a cut-

ter blade 24, which is bent down from cutter blade base 25 attached to can cover 17. Cutter blade 24 is sharp and has diverging sides so that when forced against container top 14 the point of 5 the cutter blade will puncture and shear the top 14, as will be described later. Immediately above diaphragm 22 is an operating chamber 26 into which projects an axial operating plunger 27 extending to the upper end of the rod. Just before 10 its emergence, plunger 27 is provided with threads 29 so that the plunger may be rotated from above the surface of the ground and progressed downwardly, the wrench end 30 being protected by driving cap 31 in case the rod is to be driven into the ground.

Apertures 32 are provided connecting the exterior of rod 1 with the space between cover 17 and container top 14, this space being made as small as possible. Apertures 32 may be made 20 small to exclude soil or may be filled with a fluid pervious filter material.

In operation, the nose 2 of the rod is removed on threads 4, cover 22 positioned on backing plate 21, and an exhausted sealed container placed in cavity 5. Pointed nose 2 is then replaced and screwed up tightly to force roll edge 19 against shoulder 20. The space between cover 17 and container top 14 is made to have a volume that is only a small fraction of the volume of the container, so that relatively small dilution of the sample occurs. Can cover 21 is automatically retained laterally in place by the side walls of the rod and rests between backing plate 22 and top 14 with the end of the cutter blade 24 in contact with the top of the can. The rod is then progressed into the ground, either by driving or by rotation, until the container is at a desired predetermined depth. Plunger 27 is then rotated, the lower end thereof bearing against backing plate 21, and as the plunger is rotated the backing plate pushes cover 17 ahead of it. The cutter blade 24 is then forced against top 14, punctures the top and shears through the top, as shown in Fig. 2, thus opening the container to the space 40 between the cover and the top of the container. The negative pressure in the container 6 then draws or aspirates fluids, either gas or water or both, from the soil adjacent apertures 32 until the pressures are equalized and whatever has been 45 aspirated is then in container 6. After the proper length of time has elapsed for the entrance of the fluids into container 6, operating plunger 30 is again rotated to force cover 21 tightly into engagement with top 14 of the container to give a 50 friction seal of ridges 16 of the cover, with channel 15 on the top of the container. The sample which was drawn into the container is thus sealed and the rod may be withdrawn, pointed nose 2 unscrewed and the sealed container removed, labeled 55 as to the location, depth, et cetera where the sample was taken, and set aside for analysis of the contents thereof. A new container may then be inserted and the process repeated at another location. Obviously, marks may be used on wrench end 30 of the plunger to set the positions of the plunger from the surface, corresponding to puncturing and resealing positions of the cover.

In Fig. 6, I have shown the means by which the sealed and filled containers may be attached to a gas analysis device. Fitting 8 containing diaphragm 11 is screwed to a system fitting 41 which is sealed to a vertical tube 42, the latter dividing at the top into a tube 43 going to a gas analysis apparatus under control of valve 44 and 60 to a vacuum pump or similar device through tube

45 under control of valve 46. Vertical tube 42 contains a sliding weight 47 having a pointed lower end 49 sharpened to puncture diaphragm 11 when dropped thereon. This weight 47 is 10 preferably of magnetic material and liftable to an upper position by surrounding it with solenoid 50, energizing the solenoid to attract weight 47, and lifting weight 47 by lifting the solenoid. In the upper position the solenoid may be de-energized to cause the weight to drop. The sharpened end 49 punctures the diaphragm and gas will then be admitted to tube 42. Prior, however, to the puncture of diaphragm 11, tube 42 is 15 preferably pumped out by the action of the vacuum pump with valve 46 closed and valve 42 opened. The gas analysis apparatus may then be held at a reduced pressure so that gas from the sample contained in container 8 may be released into the gas apparatus under the influence of such treatment as may be necessary to release the gas therefrom. The gas released from the container may then be analyzed in known ways, for the presence of hydrocarbons such as, for example, the combustion method, by the use of the Hertz diffusion apparatus, or by the use of a mass spectrometer as set forth in the copending application of Washburn & Taylor, Serial No. 320,802, filed February 26, 1940.

The samples can be analyzed for any of the following:

(a) Light hydrocarbons which have migrated or diffused from a petroleum deposit;

(b) Chemicals derived from migratory constituents by catalytic action of the soil and other natural forces;

(c) Any significant constituent that follows the same path as the hydrocarbons;

(d) Any migratory constituent significant of underground mineral deposits.

After the analysis has been made, the results are noted and correlated with other results obtained to endeavor to outline, on the map record kept, patterns or gradients in terms of significant gas content, which will indicate the presence or absence of a subterranean deposit.

It may be found that the extraneous gas in the space between the can top 14 and the diaphragm 22 is so large that anomalies will be entered into the sampling by the carrying of atmospheric air down to the sampling level or by the entrance of soil gas into this space during progression of the device into the ground. I therefore may find it advisable to fill the space between can top 14 and diaphragm 22 with an inert material during progression into the ground. Such inert material may be, for example, carefully distilled water. In case I use this inert material, I prefer to close apertures 32 by an exterior slide which can be withdrawn to a position opening apertures 32 after the device has reached its proper sampling depth. Such a slide has been shown and described in the co-

pending application of Lawlor and Metcalf, Serial No. 341,004, filed June 17, 1940.

I claim:

1. In the art of geochemical prospecting 5 wherein a plurality of earth content samples are systematically taken over an area to be prospected, each sample enclosed in an individual container, and the samples subsequently analyzed for constituents which are related to gases which normally migrate upward from a mineral deposit below the sampling points, the improvement which comprises exhausting each container, placing such exhausted container at a substantial depth below the surface of the earth without substantial disturbance or aeration of said soil, and wherein such soil has not been previously disturbed at any substantially near locality, by means of a tool having provision for accommodating the container as well as means operable from the earth's surface for breaking the seal and resealing the container and adapted to be driven into the soil, the container while accommodated in said tool having communication with the exterior thereof, opening the exhausted container to aspirate fluid into said container from the soil surrounding said container only, resealing said container and withdrawing the tool with the container to the surface whereby the contained sample together with others of the said plurality may be analyzed to obtain data useful in locating said deposit.

2. The method of geochemical prospecting 10 which comprises exhausting a container and sealing the same, placing such exhausted container at a substantial depth below the surface of the earth without substantial disturbance of the earth anywhere near the container, by a tool having provision for accommodating and for opening and subsequently resealing the container from the earth's surface, then exposing the interior of said container to the surrounding soil, by operation of said tool from the earth's surface, to aspirate liquids and gases from the soil, then resealing the container by operation 15 of said tool, then removing the tool and container to a position above the surface, and then removing said aspirated liquids and gases from the container.

3. The method of geochemical prospecting 15 which comprises driving into the earth to a substantial depth a tool carrying an exhausted and sealed container and having provision for opening and subsequently resealing the container from the earth's surface, without substantial disturbance of the surrounding earth, then operating the tool from the earth's surface to expose the interior of said container to aspirate and receive liquids and gases from the nearby earth, then operating the tool to seal the container 20 again, and then removing the tool with the sealed container, from the earth.

HERBERT E. METCALF.
